TILTABLE SEARCHLIGHT HAVING A HIGH
POWER ARC LAMP

Carl Büchle and Karl Prinz, Jena, Germany, assignors to the firm of Carl Zeiss, Jena, Germany

Application October 15, 1935, Serial No. 45,079
In Germany October 20, 1934

4 Claims. (Cl. 176—119)

We have filed an application in Germany, October 20, 1934.

In high-power arc-lamps having electrodes inclined relatively to each other, the smooth burning and the efficiency of the light depend largely on the positions the axes of the electrodes assume relatively to each other. It is therefore essential that the electrodes are so arranged relatively to each other that the arc is given the correct shape, which is dependent upon the currents of air arising when the lamp is burning. Accordingly, when the lamp burns in a position other than the normal one, in which the search-light axis is generally horizontal, the changed currents of air make the light-arc assume another shape, and this especially when the changes of position are comparatively great, for instance after an upward rotation of the search-light through an angle of 90° or more. A departure from the original shape of the light-arc may give rise to very noticeable disturbances especially in automatically controlling lamps, since the variation of resistance due to a different shape of the arc very often entails such a length of this arc as is substantially different from the normal one, provided, of course, that the electric voltage of the lamp remains unchanged.

According to the invention, the effects of alterations of the light-arc in high-power arc-lamps is neutralized by making the position of the cathode axis relative to the position of the anode axis so respond automatically to any inclination of the lamp relative to a vertical line that the cathode axis is always given relatively to the anode the position most favourable for the angle between the said vertical line and the axis of the search-light. Experiments have proved that it is possible in this manner to rotate the search-light even more than through an angle of 180° without an interruption of the light-arc having to be feared.

It is advisable to provide that the cathode sleeve be rotated about an axis and to use for the adjustment of the cathode holder relative to this axis a curved guide, for instance an eccentric body whose axis of rotation is parallel to that of the cathode sleeve.

The automatic adjustment of the cathode can be effected by means of a wheel gear transmitting the movement of the search-light housing to the cathode. Another suitable kind of automatic compensation of the rotation about a definite axis is obtained when the adjustment of the cathode sleeve is effected by a pendulum which is mounted in the search-light housing

and is rotatable about an axis parallel to a horizontal axis of rotation of the search light, and which is coupled to the cathode sleeve, for instance by means of the curved guide mentioned above. Pendulums for an automatic control of the cathode can be used eventually also for compensating the search-light rotation about a plurality of axes.

In the following, which is a further description of the invention, reference is had to the accompanying drawing.

In this drawing, Figures 1 and 2 illustrate the desired reciprocal positions of the electrodes in two different search-light positions; Figure 3 represents a constructional example of an arc-lamp without search-light housing; and Figure 4 is a lateral view of a search-light which is rotatable about a horizontal axis and of a different constructional form. In all these figures, the anode and the cathode are designated A and B, respectively.

Figure 1 shows the electrodes in the normal search-light position. The cathode axis U—U is inclined at an angle α relative to the anode axis V—V and intersects the end face of the anode A at the point A¹. To ensure a correct burning, this point A¹ does not coincide with, but is displaced by x^1 relatively to, the centre of the end face. When the search-light is rotated for instance upwardly through an angle of 180°, the electrodes assume the positions represented in Figure 2. According to the invention, this rotation automatically so changes the axial position of the cathode B according to the search-light adjustment that the axis U—U intersects the said end face at the point A². This point A² is displaced by x^2 relatively to the centre of the end face, A² being at that side of the said centre which is opposite A¹. Accordingly, the changed air-currents and other conditions are taken into account.

In the lamp according to Figure 3, the cathode B is held by a sleeve a rotatable about a pinion c in a support b resting on a base b¹. The sleeve a is connected to the support b also by a rod d which is longitudinally displaceable in a ring e fixed to the support b. Between this ring e and a collar d¹ fast with the rod d is provided a helical spring f which presses the sleeve a against an eccentric body g. This body g is so mounted on the support b as to be rotatable about an axle g¹, to which a pendulum g² is attached.

When the lamp is rotated upwardly, the pendulum g² and, accordingly, the eccentric body g remain in their positions relative to space. As

a consequence thereof, the position of the eccentric body g relative to the sleeve a is changed, which means that also the positions of the sleeve a and the angle α are altered. Subsequently to 5 the lamp having been rotated through 180° , the angle α has become α^1 , and the point at which the axis $U-U$ intersects the end face of the anode A has travelled from A^1 to A^2 .

In the constructional example according to 10 Figure 4, a toothed wheel a^1 is substituted for the pendulum g^2 . The base b^1 is rotatable about an axle i in a support, for instance in a fork b^2 resting on a foot b^3 . The toothed wheel a^1 is in mesh with a toothed wheel a^2 of equal diameter, this 15 wheel a^2 being fixed to the axis of rotation i of the search-light housing. Accordingly, the desired cathode displacement is possible also by means of this construction.

We claim:

- 20 1. In a search-light, a high-power arc-lamp containing a cathode and an anode inclined relatively to each other at an obtuse angle, a rotary base for the lamp, and a support for the base, this base being adjustable in the support relatively to a vertical line, means for automatically adjusting the angle of inclination of the cathode 25 relatively to the anode according to the inclination of the said base relative to the vertical line.
- 25 2. In a search-light, a high-power arc-lamp containing a cathode and an anode inclined relatively to each other at an obtuse angle, a base for the lamp, and a support for the base, a cathode sleeve, and a cathode support rigidly connected to the said base, the cathode sleeve being mounted on this cathode support and rotatable about an axis at right angles to the plane containing the axis of the cathode and anode, an eccentric body for adjusting the cathode sleeve on its axis of rotation, and means coupled to the 30 eccentric body and adapted to automatically

adjust in combination with this body the angle of inclination of the cathode relatively to the anode according to the adjustment of the said base relative to the vertical line.

3. In a search-light, a high-power arc-lamp 5 containing a cathode and an anode inclined relatively to each other at an obtuse angle, a base for the lamp, and a support, the base being so disposed in this support as to be rotatable about a horizontal axis, a cathode sleeve and a cathode 10 support rigidly connected to the said base, the cathode sleeve being mounted on this cathode support and rotatable about an axis at right angles to the plane containing the axis of the cathode and anode, an eccentric body for adjusting the cathode sleeve on its axis of rotation, a gear comprising two wheels, the one of these 15 wheels cooperating with the eccentric body, and the other of these wheels being rigidly so connected to the said support for the base as to be 20 concentric to the said axis of rotation of the base.

4. In a search-light, a high-power arc-lamp containing a cathode and an anode inclined relatively to each other at an obtuse angle, a base for the lamp, and a support, the base being so 25 disposed in this support as to be rotatable about a horizontal axis, a cathode sleeve and a cathode support rigidly connected to the said base, the cathode sleeve being mounted on this cathode support and rotatable about an axis at right 30 angles to the plane containing the axis of the cathode and anode, an eccentric body for adjusting the cathode sleeve on its axis of rotation, and a pendulum so suspended on the said cathode support as to be rotatable about an axle parallel 35 to the said horizontal axis of rotation of the said base.
